MUSICAL INSTRUMENT.

1,330,078.

Specification of Letters Patent. Patented Feb. 10, 1920.

Application filed October 16, 1919. Serial No. 330,997.

To all whom it may concern:

Be it known that I, REESE B. KENT, a citizen of the United States of America, and resident of Wheeling, county of Ohio, and State of West Virginia, have invented certain new and useful Improvements in Musical Instruments, of which the following is a specification.

This invention relates broadly to an electrical wiring system for the fingering magnets of mechanically played stringed instruments, and it has for its primary object to provide, in connection with a violin or other similar stringed instrument and associated with a player piano having key actions which are silenced and responsive to perforations in a traveling music-sheet for closing electric circuits through said magnets, means whereby a maximum number of such fingering magnets for said instrument may be rendered operative by the employment of a minimum number of silenced key-actions of such player piano.

A further object is to simplify and improve the musical instrument disclosed in my pending application for Letters Patent, Serial No. 279,249.

In describing the invention in detail reference is herein had to the accompanying drawings, in which—

Figure 1 is a diagrammatic view illustrating the invention, and—

Fig. 2 is a side elevation of a silenced key-action of a player piano showing diagrammatically the electric circuits which are closable through actuation thereof.

Referring to said drawings, 1 indicates the neck of a violin or other similar stringed instrument which has associated therewith a plurality of suitable fingering devices adapted to be actuated to move into engagement with the strings 2 by means of electromagnets located in a plurality of electric circuits which are closable for energizing said magnets. Said electric circuits are designed to be closed through engagement of movable contact members 3 with stationary contact members 4. While said contacts may be located on a player piano in any suitable position wherein they will be carried into engagement for closing the electric circuit in which they are located by operative movement of one of said parts in the usual manner occasioned by the passage of a perforation in the traveling player-piano

music-sheet over the tracker-board, it is preferred that said stationary contact 4 be mounted upon the lower flange rail 5 of the piano and that said movable contact 3 be carried by the substantially-upright vertically-movable abstract 6 of a key action which is silenced by suitable means, as by an outwardly shifted clavier bar 7 which is mounted upon the hammer-butt spring-rail 8 of the piano. Said abstract is seated at its lower end upon the rear end of the usual piano key 9 and has pivoted connection with said lower flange rail, as ordinarily. In such position, when the abstract 6 is elevated in the manner commonly produced by the actuation of the key actions of a player piano, the contact 3 is caused to engage the contact 4. This action results in the closing of the electric circuit and in energizing one of two companion fingering magnets 10 and 10^a located in separate branches of said circuit, according as the energizing current is permitted to pass through one or the other of said branches.

A switch 11 is interposed in each of the various electric circuits whereby the circuit may be closed through a selected branch thereof for energizing the magnet which is included in said branch. In the present embodiment, the various switches 11, one being employed for each circuit, are carried by and extend laterally from a longitudinally shiftable rod or bar 12 which is located in an appropriate position and which is normally held in the retracted position shown in the drawings by means of a retractile coil spring 13.

Each of the various switches 11 is connected by a conductor 14 to the movable contact 3 of one of the silenced key actions, and, in the retracted position of said bar 12, lies in engagement with a contact 15 which is connected by a conductor 16 leading to one of the fingering magnets 10 which, in turn, is connected by conductor 17 to a source of electric current, as to a pole of a storage battery 18 which has its opposite pole connected by a conductor 19 to the stationary contact 4 with which said movable contact 3 is adapted to engage.

When said bar 12 is shifted against the tension of the spring 13, the various switches 11 are carried out of engagement with the contacts 15 and into engagement with contacts 20. Each of said contacts 20 is con-

nected by a conductor 21 to a fingering magnet 10^a which is in turn connected by a conductor 22 to the conductor 17 hereinbefore referred to.

5 The bar 12, or one end thereof, constitutes the armature of an electro-magnet 23 which, when energized, acts to produce shifting of said bar against the tension of its spring 13. Said magnet 23 is included in an electric circuit which comprises the source of current 18, conductor 17, a conductor 24, said magnet 23, a conductor 25, a movable contact 3^a, a stationary contact 4^a, a conductor 26 and the conductor 19, said conductor 26 being connected to, or tapped in on, said conductor 19. Said contacts 3^a and 4^a correspond in all respects with the contacts 3 and 4 hereinbefore referred to and are actuated to engage for closing the circuit 20 through said magnet 23 by operative movement of a key-action of the piano actuated by passage of a perforation in the music-sheet over the tracker bar.

It will be understood that specially-cut 25 perforations are provided in the music-sheet for actuating the various player-piano key-actions by means of which the various electric circuits including the contacts 3 and 4 are closed, and that other specially-cut perforations are provided in said music-sheet 30 for actuating the key-action by means of which the circuit including contacts 3^a and 4^a are closed.

In practice, when a certain fingering magnet 10 is to be actuated, a perforation is provided in the music-sheet at the proper point 35 for actuating the key-action carrying the contacts 3 and 4 whereby the circuit through said magnet is closed. When a certain fingering magnet 10^a is to be actuated, two perforations are provided at proper points in the sheet, one thereof for actuating the contacts 3^a and 4^a whereby the circuit through 40 the magnet 23 is closed for effecting the shifting of rod 12 simultaneously with the actuation through the other perforation of the key-action whereby the circuit is closed 45 through said magnet 10^a.

As is obvious, the perforations for actuating the fingering magnets must be specially cut to produce fingering action of said magnets in the order and succession required in the production of the notes through the intermediacy of suitable bowing devices, as 55 the bowing disks 15 of the instrument disclosed in my application hereinbefore referred to.

It will be noted that the invention described provides for the actuation of sixty 60 fingering magnets with the employment of but thirty-four key-actions of the player-piano, (thirty for the fingering magnets 10 and 10^a and four for the switch shifting magnets 23) leaving ten key-actions to be

utilized for actuating bowing disks, pickers 65 and expression devices, and forty-four key-actions for the required piano accompaniment.

What is claimed is—

1. The combination with player-piano 70 key-actions responsive to perforations in a traveling music-sheet and having associated therewith means whereby some thereof may be silenced without wholly restraining responsive movement, of an electrical contact 75 carried by a movable part of certain of said silenced key-actions, a fixed contact member adapted to be engaged by said movable contact, an electrical circuit in which said contacts are located and adapted to be closed by 80 interengagement of said contacts, a violin or other stringed instrument, a plurality of fingering devices associated with the strings of said instrument, each fingering device including an electro-magnet, each circuit 85 having two branches and having one fingering magnet located in each branch, and means for selecting the branch through which the current is directed upon the closing 90 of the circuit. 90

2. The combination with player-piano key-actions responsive to perforations in a traveling music-sheet and having associated therewith means whereby some thereof may be silenced without wholly restraining responsive movement, of a pair of electrical contacts adapted to be interengaged by movement of a part of certain of said silenced key-actions, an electrical circuit in which 10 said contacts are located and adapted to be closed by interengagement of said contacts, a violin or other stringed instrument, a plurality of fingering devices associated with the strings of said instrument, each fingering device including an electro-magnet, each circuit 10 having a plurality of branches and having one fingering magnet located in each branch, and means for selecting the branch through which the energizing current is directed when the circuit is closed. 11

3. The combination with player-piano key-actions responsive to perforations in a traveling music-sheet and having associated therewith means whereby some thereof may be silenced without wholly restraining responsive movement, of a violin or other similar stringed instrument, a plurality of fingering devices associated with the strings of said instrument, each fingering device including an electro-magnet, a plurality of 11 normally open electric circuits each of which embodies two branches, each of said branches including one of said magnets, electrical contacts located in each of said circuits adapted to effect closing of the latter through one or 12 the other of the branches thereof, said contacts being carried by relatively movable parts of selected music-sheet-operated key- 12

actions, and means for selecting the branch of the circuit through which energizing current is directed.

4. The combination with player-piano key-actions responsive to perforations in a traveling music-sheet and having associated therewith means whereby some thereof may be silenced without wholly restraining responsive movement, of a violin or other similar stringed instrument, a plurality of fingering devices associated with the strings of said instrument, each fingering device including an electro-magnet, a plurality of normally open electric circuits each of which embodies two branches, each of said branches including one of said magnets, electrical contacts located in each of said circuits adapted to effect closing of the latter through one or the other of the branches thereof, said contacts being carried by relatively movable parts of selected music-sheet-operated key-actions, and means for selecting the branch of the circuit through which energizing current is directed, said means including a switch located in each circuit, means normally maintaining said switch in operative relation to one of said branches, and means for shifting said switch out of said relation and into like relation to the other branch.

5. The combination with player-piano key-actions responsive to perforations in a

traveling music-sheet and having associated therewith means whereby some thereof may be silenced without wholly restraining responsive movement, of a violin or other similar stringed instrument, a plurality of fingering devices associated with the strings of said instruments, each fingering device including an electro-magnet, a plurality of normally open electric circuits each of which embodies a plurality of branches, each of said branches including one of said magnets, electrical contacts located in each of said circuits adapted to effect closing of the latter through one or the other of the branches thereof, said contacts being carried by relatively movable parts of selected music-sheet-operated key-actions, and means for selecting the branch of the circuit through which energizing current is directed, said means including a switch in operative relation to one of said branches, and means responsive to perforations in said music-sheet whereby said switch is shifted from its normal position into operative relation to another of said branches.

In testimony whereof, I affix my signature in presence of two subscribing witnesses.
